(57) **CLAIM**

The ornamental design for an arborist throwing weight, as shown and described.

DESCRIPTION

FIG. 1 is a perspective view of the arborist throwing weight, showing the new design;

FIG. 2 is a front elevational view of the arborist throwing weight thereof;

FIG. 3 is a rear elevational view of the arborist throwing weight thereof;

FIG. 4 is a left side elevational view of the arborist throwing weight thereof;

FIG. 5 is a right side elevational view of the arborist throwing weight thereof;

FIG. 6 is a top plan view of the arborist throwing weight thereof; and,

FIG. 7 is a bottom plan view of the arborist throwing weight thereof.

1 Claim, 2 Drawing Sheets
